COMB CASE

John R. Skeese, Mokena, Ill.

Application August 13, 1938, Serial No. 224,794
Renewed February 9, 1940

20 Claims. (Cl. 132—28)

This invention relates to a case for a comb. The case carries a brush on each side of the case and mounted opposite in respect to each other. These brushes may be mounted permanently or may be removable.

One of the objects of this invention is to provide a carrying case for a pocket or toilet comb. Another object of the invention is to provide a comb cleaner, and a third object of 10 the invention is to provide a combination comb and brush device.

The case is so constructed that the bristles, hair or fiber of the brushes will engage the teeth of the comb when used as a comb case, combination comb and brush or comb cleaner. The 15 brushes of the case frictionally engage the teeth of the inserted comb and thus aid in holding the comb in place in the case. The case also protects the teeth of the comb against breakage and aids, when used as a carrying case, in keeping the comb clean. The case may or may 20 not be made with a slot in the bottom of the case, but the slot is preferable for the purpose of cleaning the comb more effectively.

25 Bristles, hair or fiber may be imbedded into the case, or any type of brush suitable for the purpose may be used in the case, although a twisted-in wire brush or rotary type brush is preferable. Of these brushes the bristles, hair or fiber may or may not overlap, although the 30 overlapping is more desirable. The brushes extend approximately half the length of the comb case in order that the remainder of the case may be used as a hand grip. When the smooth edge 35 of the comb is inserted in the case, the toothed edge of the comb being free for use for combing hair, by tilting the combined device slightly forward, the hair or fur may be combed and brushed in one operation to remove loose hair, dirt and 40 dandruff. With the combined device tilted in the same manner, the scalp or hide may be massaged. The case when used in this manner prevents easy breakage by giving added support to the 45 comb.

50 When the case is used as a comb cleaner, the comb is cleaned by inserting the comb perpendicularly between the pair of brushes and worked down and up. A slot in the bottom edge of the case is provided for inserting the comb to be cleaned. The brushes of the case may, if desired, be removed for cleaning or replacement.

55 The case may be made in sizes to fit either pocket or toilet combs and of any suitable material, and in a variety of colors. If desired,

colored brushes may be used in colors to match the material of the case base.

The accompanying drawing illustrates the preferred embodiment of my invention, and is as follows:

Fig. 1 is a view in side elevation of the comb case with a comb in carrying position.

Fig. 2 is a view in side elevation of the comb case.

Fig. 3 is a cross-section view taken on line 3—3 of Fig. 2.

Fig. 4 is a cross-section view taken on line 4—4 of Fig. 2.

Fig. 5 is a cross-section view taken on line 5—5 of Fig. 2.

Fig. 6 is a cross-section view taken on line 6—6 of Fig. 2.

Fig. 7 is an edge view of the bottom side of the case carrying a pair of rotary brushes.

Fig. 8 is an edge view of the top side of the case with the pair of rotary brushes removed.

Fig. 9 is a view in side elevation of the comb case with the comb in position for being cleaned.

Fig. 10 is a view in side elevation of the comb case with the comb in position for combing and/or brushing hair.

In the drawing like reference characters 11 to 16 denote corresponding parts through Figs. 2 to 8.

In Fig. 7, 11 denotes a slot on the bottom edge 30 of the case, extending about two-thirds the length of the case, through which the comb is moved down and up between the brushes for cleaning. 13 is a rotary brush shaft and 14 rotary brush bristles. In Fig. 8, a slot 12 extends 35 part way down both sides of the case. 15 is a recess for mounting one end of the brush shaft 13. 16 is an elongated slightly concave recess for mounting the other end of the brush shaft 13. Recesses 15 and 16 are placed on the same 40 plane, supporting opposite ends of the shaft 13 of the rotary brush.

To remove either brush, press member 13 inward at the elongated recess 16 until the shaft has cleared the recess. Then lift member 13, 45 dislodging it from the recess 15. However, the brushes may, if desired, be placed permanently by any suitable means, in the case. The case carries a pair of rotary brushes, each brush mounted opposite the other so that the bristles 50 14 of the brushes overlap one another, the bristles of these brushes preferably being about one-eighth of an inch long. The rotary brushes are approximately half the length of the case.

The above is a description of the preferred 55

embodiment of my invention, but this may be varied within the scope of the appended claims.

I claim:

vide a hand grip with the remainder of the case, which are constitutive elements of the case.

19. A case for carrying a comb and/or brushing hair and/or massaging the scalp and cleaning a comb, said case carrying rotary or twisted-in-wire brushes approximately half the length of the case positioned on opposite sides so that the bristles, hair or fiber of the brushes overlap one another, the bristles, hair or fiber frictionally engaging teeth of an inserted comb, the remainder of the case being a hand grip, the case having an opening formed therein.

20. A case which when used with a comb may

be used for combing and/or brushing hair, and/or massaging the scalp, and/or carrying a comb and cleaning a comb, said case carrying rotary or twisted-in-wire brushes approximately half the length of the case positioned on opposite sides so that the bristles, hair or fiber of the brushes overlap one another, the bristles, hair or fiber frictionally engaging teeth of an inserted comb, the remainder of the case being a hand grip, the brushes being removable, the case having an opening formed therein. 5 10

JOHN R. SKEESE.
